WILLIAM E. GREGG, OF FORD CITY, PENNSYLVANIA.

SAND WASHING AND GRADING APPARATUS.

1,133,721.

Specification of Letters Patent. Patented Mar. 30, 1915.

Application filed August 23, 1912. Serial No. 716,720.

To all whom it may concern:

Be it known that I, WILLIAM E. GREGG, a citizen of the United States of America, residing at Ford City, in the county of Armstrong and State of Pennsylvania, have invented certain new and useful Improvements in Sand Washing and Grading Apparatus, of which the following is a specification, reference being had therein to the accompanying drawing.

This invention relates to a sand washing and grading apparatus especially designed for grinding machines used in the production of plate glass.

15 The primary object of my invention is to provide a washing and grading device for expeditiously and economically washing and separating various grades of sand, whereby the different grades of sand can be used as 20 an abrasive material for grinding and smoothing glass and other vitreous material.

Another object of this invention is to provide an apparatus of the above type wherein positive and reliable means are used, as hereinafter set forth, for automatically grading 25 granular material, whereby a desired grade of a material can be easily obtained for a specific purpose.

A further object of this invention is to 30 provide an apparatus of the above type wherein the principle of gravity is involved for separating and positioning granular bodies or particles of various weights, the apparatus being constructed whereby different 35 grades can be withdrawn from the apparatus as occasion may require.

A still further object of this invention is to 40 provide an apparatus of the above type consisting of comparatively few parts that are inexpensive to manufacture and highly efficient for the purposes for which they are intended.

With the above and other objects in view, the invention resides in a novel construction, 45 combination and arrangement of parts to be hereinafter specifically described and then claimed.

Reference will now be had to the drawing, 50 wherein there is illustrated a preferred embodiment of the invention, but it is to be understood that the structural elements are susceptible to such changes as fall within the scope of the appended claims.

In the drawings:—Figure 1 is a side elevation of the apparatus partly broken away and partly in section, Fig. 2 is a plan of the

same, Fig. 3 is an enlarged horizontal sectional view of a clamp valve for controlling the sand grading current, and Fig. 4 is a longitudinal sectional view of the same. 60

An apparatus in accordance with this invention comprises a tapering or inverted conical-shaped container or receptacle 1 that has the side walls thereof stepped to provide a plurality of angularly disposed annular shoulders 2. The large and open end of the receptacle forms the top thereof and the lower reduced end of the receptacle is provided with an outlet pipe 2^a formed with a T-coupling 3^a. Arranged above the T-coupling 3^a in the outlet pipe 2^a is a gate valve 3 and arranged at the lower of the outlet pipe 2^a is a gate valve 3^b, the latter normally closes the lower end of the pipe 2^a. Connected to the lateral leg of the coupling 3^a is a short pipe length 3^c having secured thereto by the clamps 4 a flexible discharge pipe 12 which is used for removing the coarse sand from the receptacle 1 for supplying the same to a rotary horizontal table 11 adapted to support a sheet of glass to be operated on, or said discharge pipe 12 can be utilized to return the coarse sand to its original source. Preferably the table 11 is arranged at the side of the receptacle 1. 85

Arranged upon the discharge pipe 12 is a clamp valve for controlling the discharge from the receptacle 1 through said pipe 12, preferably the discharge is less than the supply to the receptacle 1 through the medium of the water and sand supply pipe 4^a. The clamp valve comprises a yoke 13 having a seat 13^a for the discharge pipe 12 and further includes a slide 14 provided with an extension 14^a which engages the pipe 12 for contracting it. The slide 14 is shiftably mounted in the yoke 13 and is operated through the medium of a screw 15 and a hand wheel 15^a. The screw 15 engages in a threaded plate 15^b which is secured to the yoke by the holdfast devices 15^c. 95

Extending into the receptacle 1 from the top thereof, as well as longitudinally thereof and to a point in proximity to the discharge end of the receptacle is a water and sand supply pipe 4^a which leads from a suitable source of sand and water supply (not shown) and which constitutes means for supplying sand and water to the receptacle 1. As the sand and water are supplied to the receptacle 1 the coarse sand settles to the bottom of the receptacle and as the water 100

is supplied simultaneously with the sand, the latter is agitated to that extent by the water that the sand is graded according to its fineness, that is to say, the very fine particles of sand gradually reach the top of the receptacle with the intermediate grades between the top and bottom of the receptacle. The sand is suspended by the water as the discharge through the pipe 12 is less than the intake through the pipe 4^a, it is obvious that the sand will pack and which causes to be formed what may be termed a sand grading current, the rapidity thereof being controlled by the clamp valve 10 upon the pipe 12 due to the fact that the clamp valve can control the discharge with respect to the intake.

Extending into the receptacle 1 and connected to each annular shoulder 2 is an annularly disposed outlet pipe 6 having an elbow-shaped inner end 6^a and further provided with a cut off 10. The pipes 6 are disposed downwardly at an inclination and each terminates in a flexible discharge pipe 7. The pipes 7 are termed down pipes and have their lower ends seated in openings 9 formed with a head 8. The lower ends 7^a of the pipes 7 are suitably secured to the head 8.

Connected to the upper end of the receptacle 1, as well as communicating therewith, is an overflow pipe 16 which can lead to the water and sand supply source or to any other desired point.

As above stated the apparatus is preferably located at the side of a table 11, the latter being diagrammatically illustrated as a conventional form of table as is used in glass factories for the production of plate glass. It is a well known fact that emery and other abrasive materials are employed for grinding as well as smoothing the surface of a sheet of glass. In lieu of employing emery and other expensive abrasive material, an apparatus in accordance with this invention can be employed whereby different grades of sand can be deposited upon the surface of a sheet of glass arranged upon the table. By opening the valve 3, a very coarse grade of sand can be supplied for use for the first step of grinding the sheet of glass. The coarse sand removes large irregularities and as the sheet is gradually ground, a finer and various finer grades of sand can be employed which can be obtained by opening the valves 10. As the sheet of glass nears completion, the very fine grades of sand in the upper portion of the receptacle are used and eventually the finer sand at the top of the receptacle. When the sand is supplied through any one of the down pipes 7, the coarse sand is conducted by the discharge pipe 12 to the source of sand and water supply. When the sand is supplied through any one of the down pipes

7, the valve 3 is not closed, so that the supply of sand and water through the pipe 4^a is continued to form, as before stated the sand grading current are so that the sand will pack up in receptacle 1 due to the controlling of the apparatus through the medium of the clamp valve.

When the apparatus is not in use the valve 3 is closed, the sand will pack tightly at the bottom of the receptacle 1; if the valve 3 is open there would be some difficulty as to the discharge of the sand. This is overcome by opening valve 3^a and inserting a suitable instrument up through the discharge pipe 2^a and into the receptacle 1 to loosen the sand so that free discharge can be had. After the sand has been loosened to obtain free discharge or satisfactory working of the apparatus the valve 3^a is closed and the discharge from the receptacle is had through the flexible pipe 12. The elbows 6^a at the inner ends of the pipe 6 facilitate the discharge through said pipes when the valves 10 are open.

The sand and water pipe 4^a is provided with a valve or cut off 4^b.

Owing to the construction of the receptacle the up current of the water will cause a grading of the sand, or in other words, the receptacle being small at the bottom, the current of water is so strong at this point that nothing but the very coarse sand will settle or stop at this point and as the following steps gradually increase in size the same current has to move larger bodies of water at each step which therefore decreases the current at each step and thereby grades the sand into different grades or at each step the sand is a grade finer. The reference to the steps is the various steps of the stepped receptacle.

From the foregoing it will be observed that I have devised a novel apparatus for economically washing and grading various kinds of granular material and although the apparatus is designed primarily for use in connection with the manufacture of plate glass; yet it is to be understood that it can be used for any purpose wherein it is found applicable.

What I claim is:—

1. An apparatus for the purpose set forth comprising an inverted cone-shaped stepped receptacle having an outlet medially of its lower end, a water and material supply pipe extending down into said receptacle to a point in proximity to said outlet for supplying the material thereto, a controllable discharge pipe connecting directly with said outlet and forming in connection with the steps of said receptacle a material grading current directed upwardly from the lower end of said supply pipe for separating the material into different grades, and means independent of said discharge pipe for in-

dependently discharging different grades of material.

2. In a grading apparatus, an inverted cone-shaped receptacle stepped throughout from its lower to its upper end, the steps of said receptacle providing a series of divisions forming compartments for different grades of material, the upper divisions being of greater area throughout than the lower divisions, each lower division having its upper terminus merging directly into the lower terminus of an upper division, said lowermost division having an outlet disposed medially thereof, means for simultaneously supplying the material to be separated and water to the lower portion of said receptacle, and a controllable material outlet means communicating with said outlet and associated with said supply means and with said receptacle for forming an upwardly directed material grading current.

3. In a grading apparatus, an inverted cone-shaped receptacle stepped throughout from its lower to its upper end, the steps of said receptacle providing a series of divisions forming compartments for different grades of material, the upper divisions being of greater area throughout than the lower divisions, each lower division having its upper terminus merging directly into the lower terminus of an upper division, said lowermost division having an outlet disposed medially thereof, the walls of each of said divisions being smooth throughout, means for simultaneously supplying the material to be separated and water to the lower portion of said receptacle, and a controllable material outlet means communicating with said outlet and associated with said supply means and with said receptacle for forming an upwardly directed material grading current.

4. In a grading apparatus, an inverted cone-shaped receptacle stepped throughout from its lower to its upper end, the steps of said receptacle providing a series of divisions forming compartments for different grades of material, the upper divisions being of greater area throughout than the lower divisions, each lower division having its upper terminus merging directly into the lower terminus of an upper division, said lowermost division having an outlet disposed medially thereof, means for simultaneously supplying the material to be separated and water to the lower portion of said receptacle, and a controllable material outlet means communicating with said outlet and associated with said supply means and with said receptacle for forming an upwardly directed material grading current.

5. In a grading apparatus, an inverted cone-shaped receptacle stepped throughout

from its lower to its upper end, the steps of said receptacle providing a series of divisions forming compartments for different grades of material, the upper divisions being of greater area throughout than the lower divisions, each lower division having its upper terminus merging directly into the lower terminus of an upper division, the lowermost division having an outlet disposed medially thereof, and a water and material supply pipe extending down into said receptacle, medially thereof and to a point in proximity to said outlet.

6. In a grading apparatus, an inverted cone-shaped receptacle stepped throughout from its lower to its upper end, the steps of said receptacle providing a series of divisions forming compartments for different grades of material, the upper divisions being of greater area throughout than the lower divisions, each lower division having its upper terminus merging directly into the lower terminus of an upper division, the lowermost division having an outlet disposed medially thereof, a water and material supply pipe extending down into said receptacle medially thereof and to a point in proximity to said outlet for supplying material to be graded to said receptacle, and a controllable discharge pipe connected directly with said outlet and forming in connection with the divisions of said receptacle a material grading current directed upwardly from the lower end of said supply pipe for separating the material into different grades.

7. In a grading apparatus, an inverted cone-shaped receptacle stepped throughout from its lower to its upper end, the steps of said receptacle providing a series of divisions forming compartments for different grades of material, the upper divisions being of greater area throughout than the lower divisions, each lower division having its upper terminus merging directly into the lower terminus of an upper division, the lowermost division having an outlet disposed medially thereof, a water and material supply pipe extending down into said receptacle medially thereof and to a point in proximity to said outlet for supplying material to be graded to said receptacle, a controllable discharge pipe connected directly with said outlet and forming in connection with the divisions of said receptacle a material grading current directed upwardly from the lower end of said supply pipe for separating the material into different grades, and means independent of said controllable discharge pipe for independently discharging the different grades of material from said divisions.

8. In a grading apparatus, an inverted cone-shaped receptacle stepped throughout from its lower to its upper end, the steps of

said receptacle providing a series of divisions forming compartments for different grades of material, the upper divisions being of greater area throughout than the lower divisions, each lower division having its upper terminus merging directly into the lower terminus of an upper division, the lowermost division having an outlet disposed medially thereof, certain of the divisions being 5 cylindrical and the other divisions flaring, the cylindrical divisions being alternately disposed with respect to the flaring divisions, means for conducting a supply of material and water into said receptacle to a 10 point in proximity to said outlet, and a controllable discharge pipe communicating directly with said outlet and forming in connection with said divisions a material grading current for separating the material into 15 different grades.

9. In a grading apparatus, an inverted cone-shaped receptacle stepped throughout from its lower to its upper end, the steps of said receptacle providing a series of divisions 25 forming compartments for different grades of material, the upper divisions being of greater area throughout than the lower divisions, each lower division having its upper terminus merging directly into the 30 lower terminus of an upper division, the lowermost division having an outlet, certain of said divisions being cylindrical and the other divisions flaring, the cylindrical divisions being alternately disposed with respect 35 to the flaring divisions, means for simultaneously supplying the material to be separated and water to the lower portion of said receptacle, and a controllable material outlet means communicating with said outlet 40 and associated with said supply means and with said receptacle for forming an upwardly directed material grading current.

10. In a grading apparatus, an inverted conical receptacle formed with cylindrical 45 and flaring portions, cylindrical portions merging into the lower ends of the flaring portions, means for supplying the material to be separated and water to the said receptacle, and means associated with said receptacle and with said supply means for forming 50 in connection with the supply means and receptacle an upwardly directed material grading current traveling at different speeds throughout the receptacle with the speed of 55 the current through each cylindrical portion uniform and with the speed of the current through each flaring portion gradually decreasing, the speed of the current through the lower cylindrical and flaring portions

being greater than through the upper cylindrical and flaring portions. 60

11. In a sand grading apparatus, an inverted conical receptacle formed of flaring and cylindrical portions alternately disposed with respect to each other, the upper 65 of said cylindrical portions being of greater diameter than the lower, the upper of said flaring portions being of greater diameter than the lower, means for simultaneously discharging material and water in said receptacle in close proximity to the lower end thereof, said lower end of said receptacle having an outlet pipe, and a controlling 70 material discharge pipe connected directly with said outlet pipe and forming in connection with said receptacle a supply pipe means to provide a continuous material grading current directed upwardly from the end of said supply pipe for separating the material in 75 different grades.

12. In a grading apparatus, an inverted conical receptacle having cylindrical and flaring portions alternately disposed with respect to each other thereby dividing said receptacle into divisions, the upper of said 80 cylindrical portions being of greater diameter than the lower, the upper of said flaring portions being of greater diameter than the lower, means in connection with said receptacle for supplying material and water thereto and for further providing a continuous 85 material grading current directed upwardly from the lower end of the receptacle for separating the supplied material in different 90 grades.

13. In a grading apparatus, an inverted conical receptacle having cylindrical and flaring portions, alternately disposed with respect to each other thereby dividing said receptacle into divisions, the upper of said 100 cylindrical portions being of greater diameter than the lower, the upper of said flaring portions being of greater diameter than the lower, means in connection with said receptacle for supplying material and water 105 thereto and for further providing a continuous material grading current directed upwardly from the lower end of the receptacle for separating the supplied material in different 110 grades, and means connected with said receptacle for independently discharging the material of different grades.

In testimony whereof I affix my signature in the presence of two witnesses.

WILLIAM E. GREGG.
